UNITED STATES PATENT OFFICE.

GEORGE R. SHANKLIN, OF SPRINGFIELD, ILLINOIS.

VALVE DEVICE FOR ACETYLENE-LAMPS AND THE LIKE.

1,334,506.

Specification of Letters Patent. Patented Mar. 23, 1920.

Application filed May 24, 1918. Serial No. 236,311.

To all whom it may concern:

Be it known that I, GEORGE R. SHANKLIN, a citizen of the United States, residing at Springfield, in the county of Sangamon and State of Illinois, have invented certain new and useful Improvements in Valve Devices for Acetylene-Lamps and the like, of which the following is a description.

My invention belongs to that general class of acetylene lamps provided with valves which are particularly designed to control the flow or feed of the fluid to the calcium carbid. It has for its object the production of a simple, durable and effective valve device for the purpose described, that is not likely to clog up with use, and that is reliable and durable in its operation.

To this end my invention consists in the novel construction, arrangement and combination of parts herein shown and described and more particularly pointed out in the claim.

In the drawings, wherein like reference characters indicate like or corresponding parts,

Figure 1 is a vertical central section through an acetylene gas lamp of well known form equipped with my invention;

Fig. 2 is a similar section of the lower part of the water tube and valve construction on an enlarged scale;

Fig. 3 is a transverse section on line 3—3 of Fig. 2; and

Fig. 4 is a similar section on line 4—4 of Fig. 2.

In the drawings, 1 represents the water chamber of an acetylene gas lamp of the kind which is usually used by miners. 2 is the carbid chamber, the two being adapted to be connected by a screw threaded connection as at 3. 4 is a water filling opening provided with a cap 5. The gas generated in the chamber 2 escapes through the tube 6 which is suitably equipped with a burner tip when in use.

7 is a water tube supported in the top of the water chamber 1 and extending downward therethrough into the carbid chamber, terminating preferably well within said chamber so that when in use the end will be within the body of carbid. The lower end

of the tube has formed thereon a valve seat 8. A sleeve 9 is firmly secured upon the tube 7 and extends well below the end thereof so that the valve operating within 55 the sleeve shall at no time extend below the bottom thereof. 10 is a valve stem loosely extending through the tube 7 and carrying upon its lower end a valve 11 arranged to seat upon and coöperate with the valve seat 60 on the end of the tube to control the flow of water passing therethrough. The upper end of the valve stem 10 is preferably secured to a thimble 12 which is screw threaded at 13 into the upper end of the tube 7. The 65 end of the stem 10 which extends through the upper end of the thimble 12 is bent over as at 14 to afford a convenient means for turning the valve stem to regulate the action of the valve. Arranged in line with the 70 junction of the valve seat 8 and the valve 11, the sleeve 9 is preferably provided with a plurality of slotted openings 15 so that as the valve is opened, the fluid passing through the tube may readily escape outward 75 through the sleeve. The valve is also of such relative size as to provide a space around the outer edge thereof between the valve and the sleeve as at 16, so that the fluid may readily escape at that point also. 80

The mode of operation is apparent and requires no description.

Having thus described my invention, what I claim as new and desire to secure by Letters Patent is:—

In a valve construction for acetylene lamps and the like, the combination of a vertically disposed fluid tube having a substantially continuous peripheral wall free from projections, the lower end of said tube 90 terminating in a valve seat, a valve stem loosely projecting through the tube and terminating at its lower end in a valve to engage said seat, the stem being adjustable whereby to regulate the adjustment of the 95 valve on its seat, and a sleeve fixed in position on the tube at the lower end thereof and wholly supported therefrom, the said sleeve being in closed relation at its upper end with the wall of the tube and projecting 100 a considerable distance below the lower end of the tube and all of the valve parts, where-

by to constitute an inclosing housing for the lower end of the tube and valve parts, and said sleeve having an unobstructed opening at its lower end and peripheral openings in substantial alinement with the valve seat.

In testimony whereof, I have hereunto

signed my name in the presence of two subscribing witnesses.

GEORGE R. SHANKLIN.
